CLAIM

The ornamental design for a circuit interrupter for preventing an electrically induced fire in an automotive vehicle, as shown and described.

DESCRIPTION

FIG. 1 is a front elevational view of the circuit interrupter for preventing an electrically induced fire in an automotive vehicle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof shown in use and on a reduced scale. The broken line showing of the cable and battery is included for the purpose of illustrating environmental elements only and forms no part of the claimed design.
